Specification for Design.

Patented June 1, 1920.

Application filed December 26, 1917. Serial No. 209,000. Term of patent 7 years.

To all whom it may concern:

Be it known that I, FRANK PFOUS, a citizen of the United States, residing at Coshocton, in the county of Coshocton and State of Ohio, have invented a new, original, and ornamental Design for a Cabinet for Rubber Bands, of which the following is a specification.

Referring to the drawing:—

Figure 1 is a perspective view showing my cabinet for rubber bands with the cover open.

Fig. 2 is a rear elevational view of my

cabinet for rubber bands with the cover in the same position as in Fig. 1.

I claim:

The ornamental design for a cabinet for rubber bands, substantially as shown.

In testimony that I claim the foregoing as my own, I have hereto affixed my signature in the presence of two witnesses.

FRANK PFOUS.
